United States Patent Office

Des. 203,902

Patented Feb. 22, 1966

203,902

RE-ENTRY VEHICLE OR SIMILAR ARTICLE

Frederick Raymes, Los Angeles, Calif., assignor to the
United States of America as represented by the Secretary
of the Air Force

Filed Aug. 23, 1963, Ser. No. 76,347

Term of patent 14 years

(Cl. D71—1)

FIG. 2

FIGURE 1 is a side elevational view of the re-entry vehicle or similar article showing my new design;

FIGURE 2 is a plan view of the re-entry vehicle or similar article; and

FIGURE 3 is a vertical projection illustrating a view of the re-entry vehicle or similar article from the rear thereof.

I claim:

The ornamental design for a re-entry vehicle or similar article as shown.
